UNITED STATES PATENT OFFICE.

WILLIAM H. BROWNELL, OF BROOKLYN, NEW YORK.

EASEL.

SPECIFICATION forming part of Letters Patent No. 257,653, dated May 9, 1882.

Application filed March 17, 1882. (No model.)

To all whom it may concern:

Be it known that I, WILLIAM H. BROWNELL, of Brooklyn, in the county of Kings and State of New York, have invented a new and useful Improvement in Easels, of which the following is a full, clear, and exact description.

The object of my invention is to facilitate the adjustment and placing of the canvas or other work on easels, so that the most desirable position can be obtained, according to the character of work being done; and to that end it consists in an easel-frame provided with an auxiliary and hinged frame, which carries the work-slides, and adjustable with reference to the main frame, to hold the work perpendicular or inclined, all as hereinafter described and claimed.

Reference is to be had to the accompanying drawings, forming a part of this specification, in which similar letters of reference indicate corresponding parts in all the figures.

Figure 1 is a perspective view of my improved easel arranged for use in the ordinary manner, and Fig. 2 is a perspective view of the easel arranged to hold a canvas in an overhanging or forward inclined position. Fig. 3 is an enlarged detail view, in cross-section, of the support *l*.

30 The support of the easel is a folding V-frame, consisting of a front portion, *A*, and rear supporting-legs, *B*.

a a are notched bars for preventing the frame from spreading.

35 *b* is a material-box fixed on the front *A*.

C is the auxiliary frame for supporting the canvas or other work. This is hinged at its lower end to the front portion, *A*, of the V-frame, and corresponds in width and length 40 with the front *A* above the hinges, so as to fit neatly theron when closed.

d is the usual rail or support for the work, which in this case is fitted in grooves *g* on frame *C*; and *f* is the upper holder for the work, also 45 engaging grooves *g*, formed in the side bars of frame *C*, so that the holders *f d* can be set up and down, according to the length of the frame on which the canvas or other work is mounted.

h h are bars pivoted on frame *C*, and notched to engage pins on the frame *A* to retain the 50 hinged frame *C*, as required.

By this construction the easel can be used in the ordinary manner, with the canvas inclined backward, and, when necessary or desirable, the auxiliary frame *C* can be moved 55 out to bring the work perpendicular and still farther to incline the upper part forward. This latter position is required especially in the painting of tapestry, when dye-colors are used, to prevent dropping of the colors upon the tap- 60 estry.

For work of unusual length, which projects above the easel, I provide the hooks or clasps *i i*, attached by elastic bands *k* to the upper part of frame *C*. These are to be turned up 65 behind the frame and caught upon the upper edge of the stretcher, as shown by dotted lines. The elastic bands will draw out to the length required and aid in holding the work tightly.

The frame *C* is also provided with supports *l l* for sustaining the work in case the stretcher is wider than the easel. These supports consist of strips of wood or other material, and, as shown in Fig. 3, are fitted in dovetail grooves 75 in the top bar of the frame, so that they may be slid in and out. They may, however, be attached in any suitable manner and placed on the side bars.

It will be understood that the rail *f* is removed when the clasps *i* are in use.

Having thus described my invention, I claim as new and desire to secure by Letters Patent—

1. The combination, with the main frame, of an auxiliary frame, *C*, carrying the work-slides 85 and hinged at its lower end to the front of the main frame, whereby the frame *C* may be adjusted with respect to the main frame to hold the work in varying positions, as described.

2. The clasps *i* and bands *k*, in combination 90 with the easel-frame *C*, substantially as and for the purpose described.

WILLIAM H. BROWNELL.
